[57] CLAIM

The ornamental design for a chair body, as shown and described.

DESCRIPTION

FIG. 1 is a front elevational view of a chair body showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a perspective view thereof.

FIG. 7 has been shown on an enlarged scale. The broken line showing of a chair base in FIG. 7 is for illustrative purposes only and forms no part of the claimed design.
